UNITED STATES PATENT OFFICE.

CHARLES SCHINDLER, OF TOLEDO, OHIO.

AMUSEMENT DEVICE.

Application filed March 24, 1922. Serial No. 546,494.

To all whom it may concern:

Be it known that I, CHARLES SCHINDLER, a citizen of the United States, and a resident of Toledo, in the county of Lucas and 5 State of Ohio, have made an Invention appertaining to an Amusement Device; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to novelty devices, and more particularly to those for advertising purposes, and has for its object the provision of a simple, efficient and inexpensive device of this character which is attractive and amusing in its nature.

20 The invention is fully described in the following specification and while, in its broader aspect it is capable of embodiment in numerous forms, a preferred embodiment 25 thereof is illustrated in the accompanying drawings, in which,—

Fig. 1 is a perspective view of a device embodying the invention illustrating the manner of using the same, and Fig. 2 is a 30 side elevation thereof with a portion of the handle broken away.

Referring to the drawings, 1 designates a 35 rod or handle member having a longitudinally extending corrugated surface, whereby by the rapid movement of a match, nail or other small object or of the thumb nail of a hand along the rod in contact therewith will impart vibration thereto. This rod is preferably of heavy wire which is longitudinally 40 crimped to provide successive undulations or corrugations therein.

Fixed to one end of the rod crosswise thereof is a clip or card holder 2, which in the present instance, comprises a strip of sheet 45 metal doubled quite closely upon itself to adapt a card 3 or other flat object to have its edge portion inserted between and frictionally gripped by the opposed leg portions or side walls of the clip. The rod 1 is connected to the clip at its base portion with the open or card receiving edge of the clip projecting upward therefrom.

The card 3 may have any advertising or other matter displayed thereon, as, for instance, the representation of an automobile

in the act of being driven and having the exposed side wheels thereof formed by discs 4, which are mounted for free rotary movements on stub spindles 5 rigidly projecting from the card in proper position to form the 60 wheel receiving spindles of the automobile shown thereby.

In the use of the device the rod or handle 1 is held in one hand and the same is vibrated by moving the thumb nail of the 65 other hand or some other firm object successively lengthwise of the rod in contact with the corrugations thereof and the vibrations thus imparted to the rod will be communicated to the card 3 carried thereby and effect 70 a rapid spinning of the wheels of the rotary members 4 on the spindles 5.

It is evident that cards having different 75 designs or illustrations thereon, and different forms and types of rotating members, may be provided and successively or selectively placed in engagement with the holding clip 2 and then vibrated in the manner described to effect a rotation of the rotatable members to indicate a rapid movement 80 of the rotating parts of the article illustrated.

I wish it understood that my invention is not limited to any specific arrangement, construction or form of the parts, as it is 85 capable of embodiment in numerous forms without departing from the spirit of the claims.

Having thus described my invention, what I claim as new, and desire to secure by Letters Patent, is,—

1. In a device of the class described, an elongated handle having a corrugated surface extending lengthwise thereof whereby the movement of an object along the handle 95 in coaction with its corrugations will impart vibrations thereto, a card carried by an end portion of the handle whereby vibration is imparted from one to the other, the card illustrating a device having rotatable parts, 100 and members carried for loose rotation by the card and representing said parts, said members having rotation imparted thereto by a vibration of the card.

2. A device of the class described, having 105 a longitudinally corrugated handle member with a card holding clip at one end, a card releasably held by said clip, and a member mounted on the card for free rotary movements when the card is vibrated, vibration 110

being imparted to the card by movement of an object along the corrugated portion of the handle in coaction therewith.

3. A device of the class described, having a handle provided with longitudinally extending corrugations, a cross clip carried by an end of the handle and having opposed card gripping portions extending upward from the handle, a card adapted to be reasonably held between the jaws of the clip and having an object with rotating parts

represented thereon, studs projecting from the card in the axes of said parts and members mounted for free rotation on the studs and representing the rotatable parts of the object, said rotatable members being rapidly rotated by vibration communicated to the card from a vibration of the handle. 15

In testimony whereof, I have hereunto subscribed my name to this specification.

CHARLES SCHINDLER.
